UNITED STATES PATENT OFFICE

HENRY KERSHAW, OF JERSEY CITY, NEW JERSEY

DESIGN FOR AN ASH TRAY

Application filed May 31, 1930. Serial No. 35,869. Term of patent 3½ years.

To all whom it may concern:

Be it known that I, HENRY KERSHAW, a citizen of the United States, residing at Jersey City, in the county of Hudson and State of New Jersey, have invented a new, original, and ornamental Design for an Ash Tray, of which the following is a specification, reference being had to the accompanying drawings, forming part thereof.

I claim:

The ornamental design for an ash tray as shown.

HENRY KERSHAW.
